HENRY B. OATLEY. Inventor

By HIS Attorney C.V. Kiehl

UNITED STATES PATENT OFFICE.

HENRY B. OATLEY, OF FLUSHING, NEW YORK, ASSIGNOR TO THE SUPERHEATER COMPANY, OF NEW YORK, N. Y., A CORPORATION OF DELAWARE.

LOCOMOTIVE DRAFT APPLIANCE.

1,372,976.

Specification of Letters Patent.

Patented Mar. 29, 1921.

Application filed December 5, 1919. Serial No. 342,590.

To all whom it may concern:

Be it known that I, HENRY B. OATLEY, citizen of the United States, and resident of Flushing, Long Island, in the county of 5 Queens and State of New York, have invented certain new and useful Improvements in Locomotive Draft Appliances, of which the following is a specification.

This invention relates to locomotives and 10 particularly to the arrangement of the front end and the draft creating appliance.

In modern locomotive practice the amount of fuel consumed in the firebox has increased to such proportions that considerable difficulty is experienced in getting rid of the 15 products of combustion at the front end; and the purpose of the present invention is to effect a front end arrangement which will improve these conditions.

20 The invention is illustrated in three figures, of which Figure 1 is a longitudinal central section of a front end of a locomotive showing my improvement. Fig. 2 is a section on line 2—2 of Fig. 1. Fig. 3 is a section on line 3—3 of Fig. 2.

The tubesheet 1 which separates the smokebox from the water and steam space has secured to it, in the usual way, the superheater flues 2 and the fire tubes 3. These 30 deliver the products of combustion from the firebox to the smokebox in the usual manner. The dry pipe 4 delivers saturated steam to the superheater header 5 which steam circulates through the superheater units 6 and 35 is returned by them in a superheated state to the superheated steam chamber 7 of the header 5, whence it leaves for the valve chests through the steam pipes 8—8. The diaphragm 9, table plate 10 and deflector 40 plate 11 set off a portion of the smokebox space in the usual manner. The gas flow through the flues 2 is controlled by the damper 12.

All of the parts so far mentioned are of 45 the usual construction.

In the form ordinarily given to the exhaust pipe 13 this pipe is cylindrical in form from its base to its tip and the space 50 14 at each side of this exhaust pipe below the table plate 10 becomes rather restricted as the size of this exhaust pipe is increased. In the form I give to the exhaust pipe 13 and to the nozzle 15, the cross section changes from circular at the base to one very much 55 elongated from front to back at the top,

In this manner I manage to increase by a considerable amount the area left at each side of the exhaust pipe 13 below the table plate, thus making the passage for the products of combustion less restricted. 60

Above the table plate I give the petticoat pipe 16 and the stack 17 shapes to correspond to the shape of the nozzle and thereby likewise improve conditions for the egress of the gases. It will be noted that the petticoat pipe 16 and the stack 17 are elongated from front to back to an extent corresponding to the elongation of the nozzle 15. This 65 secures a twofold advantage. In the first place, the flattening of the nozzle, petticoat 70 pipe, and stack secures an increased ejecting effect of the steam jet issuing from the nozzle. To this increased draft producing action *per se* I lay no claim as it is well known. By the particular position I give 75 to the parts mentioned, however, I secure the advantage that gases going through the netting of the deflector plate 11 are freer to pass on each side of the petticoat pipe 16 and into the stack 17 or the petticoat pipe 80 than they would be in case the stack and petticoat pipe were circular in section or were placed in any other position than that of my arrangement. In other words, the space on each side of the petticoat pipe and 85 stack is very much larger with my arrangement than it has been hitherto.

I am quite aware that it has been suggested to place a flattened nozzle and the accompanying flattened petticoat pipe and stack 90 transversely to the axis of the locomotive. The advantages obtained in my arrangement are evidently not secured in such an arrangement and in fact quite the opposite happens, the gases being allowed to pass 95 into the petticoat pipe and stack only along the front edge, the rear edge being practically ineffective. With my arrangement on the other hand, practically the entire circumference of the lower edges of the petticoat pipe and smoke stack admit products of combustion. 100

An additional though minor advantage which I wish to point out is that by flattening the smoke stack and placing it in the 105 position I do I diminish the head resistance offered by the air when the locomotive is in motion.

It will be obvious that variations may be introduced in practice without departing 110

from the spirit of my invention. Thus, while I have shown a typical arrangement using a petticoat pipe, it will be clear that the principle disclosed herein can be equally well used in cases where there is merely a stack extension and no petticoat pipe proper. In fact, the particular netting arrangement I have shown in illustrating my invention must not be thought to be the only one with 10 which my invention can be used. On the contrary, the advantages of my invention can be secured with almost any of the front end arrangements hitherto proposed.

What I claim is:

- 15 1. In apparatus of the class described, the combination of a flue sheet, flues with their ends secured to said flue sheet, a cylindrical smokebox extending from the flue sheet, a smoke stack of an elongated cross-sectional 20 shape extending through the wall of the smokebox with its greater dimension parallel to the axis of the smokebox and an exhaust pipe alined with the smoke stack and having a correspondingly shaped nozzle.
- 25 2. In apparatus of the class described, the combination of a flue sheet, flues with their ends secured to said flue sheet, a cylindrical smokebox extending from the flue sheet, a smoke stack of an elongated cross-sectional 30 shape extending through the wall of the

smokebox with its greater dimension parallel to the axis of the smokebox; a diaphragm plate, table plate, and deflector plate inclosing the space into which the inner end of the stack extends; and an exhaust pipe, extending through the table plate, and alined with the smoke stack and having its upper portion and nozzle shaped to correspond to the shape of the stack. 35

3. In apparatus of the class described, the combination of a flue sheet, flues with their ends secured to said flue sheet, a cylindrical smokebox extending from the flue sheet, a smoke stack of an elongated cross-sectional shape extending through the wall of the 40 smoke box with its greater dimension parallel to the axis of the smokebox; a petticoat pipe of correspondingly elongated cross-section, alined with the stack; a diaphragm plate, table plate, and deflector plate 45 inclosing the space surrounding the stack and petticoat pipe; and an exhaust pipe, extending through the table plate, and alined with the smoke stack and petticoat pipe and having its upper portion and nozzle shaped 50 to correspond to their shape. 55

Signed at New York, in the county of New York and State of New York, this 3d day of December, A. D. 1919.

HENRY B. OATLEY.
